UNITED STATES PATENT OFFICE.

SAMUEL A. STRZELCZYK, OF MILWAUKEE, WISCONSIN.

MILK-BOTTLE CAP REMOVER.

Application filed September 18, 1922. Serial No. 588,882.

To all whom it may concern:

Be it known that I, SAMUEL A. STRZELCZYK, a citizen of the United States, and resident of Milwaukee, in the county of Milwaukee and State of Wisconsin, have invented certain new and useful Improvements in Milk-Bottle Cap Removers; and I do hereby declare that the following is a full, clear, and exact description thereof.

This invention relates to improvements in devices for removing paper caps on milk bottles, and comprises a suitable tool for piercing the milk bottle cap, said tool being rigidly secured to the wall, or other suitable support, by means of a bracket, and a resilient guard surrounding the tool, said guard serving to prevent accidental contact with the point of the tool and also serving to assist in the removal of the paper cap from the tool.

The object of the present invention resides broadly in the provision of means adapted to form a guard for the cap removing tool, said means serving to limit the entrance of the tool into the cap, and also assisting in the removal of the cap from the tool.

With the foregoing and other objects in view, the invention consists in what is herein shown and described and more particularly pointed out and defined by the appended claim.

While I have shown one embodiment of the invention, it will be appreciated that various changes in details of construction and arrangement of parts are contemplated as within the scope of the invention.

In the drawings,—

Figure 1 is an elevational view of the present invention illustrating the same associated with a milk bottle provided with a paper cap.

Figure 2 is a bottom plan view, and

Figure 3 is a transverse sectional view taken on the line 3—3 of Figure 2.

Referring now more particularly to the accompanying drawing, the numeral 1 designates a U-shaped attaching bracket provided with extended arms 2 and 3. The bracket is notched out at 4 for the reception of a retaining screw 5, the bracket being rigidly secured in place by the head of the screw. When it is desired to remove the device for the purpose of washing or clean-

ing the same, the screw 5 is merely loosened 55 and the bracket may then be readily detached without necessitating removal of the screw.

The extended arm 2 is provided with a V-shaped notch 6, the sides of which are 60 sharpened to a fine edge which serves as a useful tool in cutting cord or string.

The end 7 of the arm 3 is clamped back upon the arm for the purpose of securing the depending barbed prong 8, together with one 65 end of a helical coil spring 9, which spring surrounds the barbed prong 8 and serves as a guard to prevent accidental contact with the point of the same.

In the operation of the device, the bottle 70 A, illustrated in Figure 1, is positioned below the prong and is centered with relation thereto by the lower coil of the helical spring. The bottle is then shoved upwardly, causing the prong 8 to pierce the 75 paper cap B, during which operation the spring 9 is compressed. As the bottle is lowered, the barbed end of the prong engages the cap and withdraws the same from the bottle. A slight downward tension exerted on the spring 9 will then cause the cap to be forced off the end of the prong.

While I prefer to construct the spring 9 in helical form, it is obvious that a straight coil spring would act equally as well. However, the advantage of the helical spring resides in the fact that the same can be more rigidly positioned with relation to the prong.

It will be further understood that various 90 modifications in the specific details of construction are contemplated as within the terms of the appended claim.

I claim:

In a device of the character described, 95 comprising an attaching bracket, a barbed prong depending therefrom, and a coil spring normally surrounding the end of the prong and serving as a guard for the same, said spring having one end rigidly connected with the prong, and the other end free to center a bottle with relation to the prong and permit the cap to be impinged thereon.

In testimony that I claim the foregoing I have hereunto set my hand at Milwaukee, in 105 the county of Milwaukee and State of Wisconsin.

SAMUEL A. STRZELCZYK.
